UNITED STATES PATENT OFFICE

153,678

DESIGN FOR A SOCKET FOR USE WITH CLIP AND LIGHT BULB

Robert K. Grubb, Portland, Oreg., assignor to
On-A-Lite Corporation, Portland, Oreg., a corporation of Oregon

Application December 30, 1947, Serial No. 143,430

Term of patent 14 years

(Cl. D26—1)

To all whom it may concern:

Be it known that I, Robert K. Grubb, a citizen of the United States and a resident of Portland, in the county of Multnomah, State of Oregon, have invented a new, original, and ornamental Design for a Socket for Use With Clip and Light Bulb, of which the following is a specification, reference being had to the accompanying drawings, forming a part thereof.

In the drawings:

Figure 1 is a perspective view showing my new design for a socket for use with clip and light bulb.

Figure 2 is a top plan view of the socket, and Figure 3 is a side elevational view of the socket.

The broken line showing the clip and light bulb is for illustration purposes only.

I claim:

The ornamental design for a socket for use with clip and light bulb, as shown and described.

ROBERT K. GRUBB.
